[57] CLAIM

The ornamental design for a lockable delivery box for entertainment articles, as shown and described.

DESCRIPTION

FIG. 1 is a front perspective view of a lockable delivery box for entertainment articles showing my new design; FIG. 2 is a rear perspective view thereof, this view showing the delivery box in an inverted condition; and, FIG. 3 is a top plan view thereof, this view being taken along line 3—3 of FIG. 1 and with its door removed for ease of illustration.

FIG. 3
